(57) **CLAIM**

The ornamental design for a product packaging, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front elevational view of a first embodiment of a product packaging;

FIG. 2 is a rear elevational view of the product packaging of FIG. 1;

FIG. 3 is a right side elevational view of the product packaging of FIG. 1;

FIG. 4 is a left side elevational view of the product packaging of FIG. 1;

FIG. 5 is a top plan view of the product packaging of FIG. 1;

FIG. 6 is a bottom plan view of the product packaging of FIG. 1; and,

FIG. 7 is a front elevational view of another embodiment of a product packaging.

The dash-dash-dash lines are for the purpose of illustrating portions of the product packaging that form no part of the claimed design.
